US00D850510S

(12) **United States Design Patent** (10) **Patent No.:** **US D850,510 S**
(45) **Date of Patent:** **** Jun. 4, 2019**

(54) **UNDERWATER FISHING CAMERA**

(71) Applicant: **GoFish Cam, Inc.**, Austin, TX (US)

(72) Inventors: **Brandon Austin**, Thornhill (CA); **Ryan Austin**, Thornhill (CA); **Benjamin Derek Litteral**, Austin, TX (US); **Kieran Howlett**, Houston, TX (US); **Roy Paul Prosise**, Austin, TX (US); **Daniel Caputo**, Austin, TX (US)

(73) Assignee: **GoFish Cam, Inc.**, Austin, TX (US)

(**) Term: **15 Years**

(21) Appl. No.: **29/613,155**

(22) Filed: **Aug. 8, 2017**
